UNITED STATES PATENT OFFICE.

FRANCIS PETELER, OF MINNEAPOLIS, MINNESOTA.

DUMPING-CAR.

No. 846,137.

Specification of Letters Patent.

Patented March 5, 1907.

Application filed November 30, 1906. Serial No. 845,712.

To all whom it may concern:

Be it known that I, FRANCIS PETELER, of Minneapolis, Hennepin county, Minnesota, have invented certain new and useful Improvements in Dumping-Cars, of which the following is a specification.

My invention relates to portable dumping-cars; and the object of the invention is to simplify and improve the form of bolster that takes the place of the side chains in my patent of August 5, 1902, No. 706,254, and particularly to improve the means for operating this bolster and reduce the cost of manufacturing and applying the same.

The invention consists generally in various constructions and combinations, all as hereinafter described, and particularly pointed out in the claims.

In the accompanying drawings, forming part of this specification, Figure 1 is a side elevation of a dumping-car embodying my invention. Fig. 2 is an end view of the same. Fig. 3 is a similar view, showing the car-body in its dumping position. Fig. 4 is a detail view of the mechanism for operating the swinging bolster.

In the drawing, 2 represents the truck-frame, having a car-body supported thereon by means of the eccentric bearings shown and described in Letters Patent of the United States, issued to me August 28, 1906, No. 829,667. This car-body is provided with doors 4 on each side, operated by means of levers 5, pivoted at 6 on cross-bars 7, connecting the upper ends of upright standards 8, that are secured to the truck-frame at each end of the car. This manner of supporting and operating the doors forms the subject-matter of a pending application for patent filed by me September 29, 1906, Serial No. 336,775.

In place of the chains usually used for preventing premature tilting of the car-body toward either side I provide bolster devices, one on each side of the car, and will now proceed to describe one of them in detail in connection with its operating mechanism, it being understood that the other bolster is substantially the same and is operated in a similar manner.

Referring to Fig. 1, 9 represents bars, preferably of metal, pivoted at 10 to the truck-frame and having laterally-turned upper ends whereon antifriction-wheels 11 are mounted in position to engage the under side of the car-body when the bars are swung to a

vertical position and prevent premature tilting of said body. I prefer to employ the simple form of construction shown in Fig. 1, which consists of flat metallic bars having 60 their lower ends pivoted, as stated, and twisted at a point intermediate to their upper and lower ends to present a flat surface to which the ends of a wooden connecting cross-piece 12 are secured. I also prefer to provide straps 13 at the lower ends of the bars for the purpose of bracing and strengthening them at their pivotal point. To swing the bars from an operative to an inoperative position, or vice versa, I provide a rock-shaft 14, 70 pivoted at 15 on the truck-frame and having its inner end near the middle transverse line of the car and provided with a crank 16, having a forked end that is pivotally connected with the middle portion of the cross-piece 12 by a link 17. A longer crank 18 is provided at the other end of the shaft extending oppositely from the crank 16 and pivotally connected to an operating-rod 19, having a handle 20 and slideable in a guide 21 on a cross-bar 22, that connects the upright standards 8. For the purpose of locking this operating-rod and the rock-shaft against premature movement I provide an offset 23 in said rod, into which the lower portion of the guide 21 85 is adapted to slip and positively hold the rod and shaft against premature movement. (See Fig. 2.) In this position the crank 16 will be swung to a substantially horizontal position and the link 17 will be in line with it 90 and will lock the swinging bolster in a substantially vertical position, where it will prevent the car-body from tilting toward that side. The handle portion 20 will project beyond the said standards 8, where it can be 95 conveniently reached by the operator. When it is desired to dump the load, the operating-rod 19 will be lifted in its guide and moved lengthwise, whereupon the shaft 14 will be rocked, the crank 16 will be swung downwardly and the bolster tilted inwardly on its pivots to the position shown in Fig. 3, where it will allow the unobstructed tilting of the car-body and the discharge of the load. As soon as the car has been returned to its normal position the operator will grasp the handle 20 and swing the bolster back to its locking position beneath the body of the car. The bolster on the other side of the car is operated in the same manner, the operating-rod 110 being oppositely arranged at the other end of the car.

I claim as my invention—

1. The combination, with a dumping-car, of a swinging bolster arranged to prevent premature tilting of the car-body, a rock-shaft having cranks, one of said cranks having a pivotal connection with said bolster and an operating-rod pivotally connected to the other crank, substantially as described.
10. 2. The combination, with a dumping-car, of a bolster adapted to prevent premature tilting of the car-body, said bolster comprising metal bars pivoted at their lower ends on the truck-frame, and antifriction-wheels mounted on the upper ends of said bars and adapted to engage the under side of the car-body, a cross-piece connecting said bars and longitudinally-movable means at each end of the car for swinging said bars and cross-piece to an upright position or to an inoperative inclined position.
15. 3. The combination, with a dumping-car, of castings secured to the truck-frame, bars pivoted on said castings, and having straps 25 13, antifriction-wheels mounted on the upper ends of said bars and adapted to engage the under side of the car-body, a cross-piece 12 connecting said bars, and means for swinging said bars to an upright operative position or 30 to an inclined inoperative position.
35. 4. The combination, with a truck-frame, of a swinging bolster mounted thereon, a rock-shaft pivoted on said frame parallel substantially with said bolster and extending 40 from a point near the middle of said bolster to the end of said frame, said shaft having a crank at its inner end and a link connecting it with said cross-piece, and said shaft having also a crank at its outer end extending in the opposite direction from said first-named crank, and means for rocking said shaft to operate said bolster.
45. 5. The combination, with a dumping-car, of a swinging bolster mounted thereon and adapted to prevent premature tilting of the car-body, a rock-shaft having a crank at one end pivotally connected with said bolster, and a second crank at its other end, an oper- 50 ating-rod pivotally connected to said second crank and having an offset, and a guide 55 wherein said rod is slid able and adapted to enter said offset and lock said rod against longitudinal movement.
6. The combination, with a truck-frame and a dumping-car mounted thereon, of a 60 swinging bolster mounted on said frame, and arranged to prevent premature tilting of said car, standards 8 mounted on said truck-frame at the end of the car, a cross-bar 22 connecting said standards, an operating-rod 65 19 slid able in a guide 21 on said cross-bar and having an offset 23 adapted to receive said guide and means operatively connecting said rod with said bolster, whereby the longitudinal movement of said rod will swing said 70 bolster to an operative or inoperative position.
7. The combination, with a dumping-car arranged to tilt toward each side, of swinging bolsters provided on the truck-frame on each 75 side of the car and arranged to prevent premature tilting of the car-body, rock-shafts mounted on said truck-frame and having cranks, means pivotally connecting one of said cranks on each shaft to the bolsters respectively, and operating-rods pivotally connected with the other cranks respectively, and whereby said shafts will be rocked and said bolsters swung to an operative or inoperative position.
8. The combination, with a dumping-car, of a swinging bolster mounted thereon and adapted to prevent premature tilting of the car, an operating-rod provided at one end of the car and having an offset, a guide wherein 85 said rod is slid able and adapted to enter said offset to lock said rod against longitudinal movement, and a rock-shaft operatively connected with said rod and bolster.

In witness whereof I have hereunto set my hand this 27th day of November, 1906.

FRANCIS PETELER.
